PUSH-BUTTON BITURN SINGLE-POLE
SWITCH

John A. Ginard, New York, N. Y.

Application August 5, 1950, Serial No. 177,893

4 Claims. (Cl. 200—159)

1

This invention relates to a push button bi-turn single pole switch.

It is an object of the present invention to provide a switch which is pushed to turn on the switch, but which requires the turning of a knob in one direction or the other to effect the opening of the switch whereby accidental tripping of a switch is prevented since the knob has to be turned by hand to open the switch, and wherein there is no doubt between the on and off positions of the switch.

Other objects of the invention are to provide a push button single pole switch which is of simple construction, inexpensive to manufacture, has a minimum number of parts, positive in operation, easy to install in a wall receptacle, compact, easily actuated and efficient in operation.

For other objects and for a better understanding of the invention, reference may be had to the following detailed description taken in connection with the accompanying drawing, in which

Fig. 1 is a longitudinal sectional view of the switch embodying the features of the present invention with the switch parts in their off positions.

Fig. 2 is a longitudinal sectional view similar to Fig. 1 with the switch parts in their switch on positions.

Figs. 3a, 3b and 3c are detail sectional views showing respectively three positions of the operating roller in the slots of the movable terminal.

Fig. 4 is a vertical sectional view taken generally on line 4—4 of Fig. 2 and looking upon the spring switch contacts spaced from one another.

Fig. 5 is a fragmentary sectional view taken generally on line 5—5 and through the movable bridging contact block.

Fig. 6 is a collective and perspective view of the push button and the turn knob parts.

Fig. 7 is a fragmentary view looking upon the interior of the casing and upon the pivot block supports.

Fig. 8 is a front elevational view of the switch and looking upon the end of the push button and upon the end of the operating knob.

Referring now to the figures, 10 represents a switch housing formed of insulating material in which is connected spaced contacts 11 and 12, a pivot block 13 having a bridging contact 14 of U-shape and a bent leaf spring 15 engaging with the movable terminal block 13 and anchored by a rivet 16 in the upper part of the switch housing 10. The front of the switch housing is closed and a metal attaching plate 17 adapted to fix the switch in a wall receptacle is connected to this front portion by screws 18 which also extend into

2

a supporting body 19 of a plunger 21 to secure the supporting body, the attaching member 17 to the front portion of the housing 10. The push button 21 has a thumb-engaging face 22 by which the member 21 is pushed. The push button 21 has an extension 23 which is connected to a roller or transverse bar 24 and operates in elongated slots 25 of the movable contact supporting member 13. This member 13 is connected by a pivot pin 26 having its respective ends disposed in openings 27 in pivot pin supports 28 connected by screws 29 and 30 to the inner wall of the switch housing 10. These pivot pin supports are arranged in opposed relationship on the respective 10 opposite sides of the housing 10 and receive respectively the respective ends of the pivot pin 26. The pivot pin 26 extends through an elongated slot 31. Rollers or bearing pins 32 and 33 are also disposed in the slot 31 to make easy the 15 operation of the movable contact supporting member 13. The movable bridging contact 14 is fixed to the top face of the supporting body 13 by screw 34, Fig. 5. In one side of the supporting body 13 is a groove 36 in which the end of 20 the bent spring 15, as indicated at 38, rides. This groove extends over the end of the supporting member and joins with groove 39 that extends in a plane running at an angle from which the groove 33 runs. An abrupt corner is accordingly afforded over which the portion 38 of the spring 25 can pass to positively hold the movable contact supporting member 13 and the movable contact 14 in a raised position, as shown in Fig. 2. If pressure is brought to bear on the plunger 21, the bar 24 will push against the walls of the slot 30 25 to pivot the movable contact supporting member 13 about the pin axis 26 until the portion 38 of the spring 15 rides over corner 40 and into groove 39 whereby to force the bridging contact 14 into positive engagement with the spring contact terminals 11 and 12 to establish a circuit through the switch. The member 13 will come to a stop when the bar 24 is in the upper end of the slots 25. The movable contact supporting member 13 will be held against the bar 24 by 35 the spring 15.

The terminal 11 is held in place in the housing 10 by a screw 41 and an electrical supply wire 42 is connected to this terminal 11 by a terminal screw 43, Fig. 4. The spring contact 12 is held 40 in place by a screw 44 and a wire 45 is connected to the contact 12 by screw 46.

The plunger 21 will be locked in its pushed in position and against the action of its spring 46 acting against the attaching member 17 by 45 the stronger action of the bent leaf spring 15.

The push button face 22 will lie within a turn knob 47 which has diametrically opposed inner wall slots 48 and 49. The push button 21 has arm projections 51 and 52 which slide respectively in the slots 48 and 49. Through this connection, the turn knob can serve to rotate the plunger 21. The turn knob is connected to a ring 53 by screws 54 and 55 operable respectively in slots 56 and 57. These screws 54 and 55 enter respectively threaded openings 58 and 59 of the knob 47. Slots of arcuate shape are provided in the plunger supporting member 19 to accommodate the heads of the respective screws 54 and 55. Screws 61 and 62 fix the ring 53 to the plunger supporting member 19.

In order to keep the plunger 21 against rotation when the switch is pushed on and as viewed in Fig. 1, a spring detent 63 extends into a longitudinally extending slot in the plunger. As the plunger 21 is pushed, this detent will ride out of the slot 64 as shown in Fig. 2. When the detent is out of the slot, the plunger can be rotated.

To open the switch contacts, the knob 47 is turned and since the plunger is coupled with the knob the plunger will be turned and likewise the bar 24 in the slots 25 of the movable contact supporting member 13 will cause the movable contact supporting member 13 to be pivoted in a counterclockwise direction, as viewed in Fig. 2, so that the portion 38 of the spring 15 will ride over the corner 40 and into the groove 36 and assisted by coil spring 46 and spacing between pin 33 and edge of slot 31 to cause a counterclockwise direction of contact supporting member 13. The bar 24 in slot 25 is now positioned as in Fig. 3b, with member 13 in off position. Releasing finger pressure from knob 47 spring 46 in Fig. 2 pushes outwardly the plunger 21 rotating knob 47 to original off position as in Fig. 1.

It will be noted that in Fig. 6 the angle grooves formed by 65 and 66 on the plunger 21, will produce a slight outward motion during the cycle of the knob 47 being turned for the off position of the switch. The knob 47 can be turned in either direction to effect the opening of the switch. The groove 64 will be brought into alignment with the detent pin 63 when the bar 24 is straightened in the lower end of the slots 25 as shown in Fig. 3c. The turning action of the bar 24 is illustrated in Fig. 3b.

It will now be apparent that to close this switch and bridge contacts 11 and 12 that one needs only to press the push button 21. The push button is moved inwardly and out of the way and is concealed by the turn knob 47. There is little chance of the switch being opened by accident. A positive action must be effected upon the turn knob to open the switch.

While various changes may be made in the detail construction, it shall be understood that such changes shall be within the spirit and scope of the present invention as defined by the appended claims.

Having thus set forth and disclosed the nature of my invention, what is claimed is:

1. A push button bi-turn single pole switch comprising a switch housing, fixed contacts connected to the housing, a movable contact adapted to engage with the fixed contacts, a movable contact supporting block pivotally connected to the switch housing, said block having a corner edge, a leaf spring having an end rideable over the corner edge, said block having elongated

slots, push button means having a transverse portion extending into the slots of the movable contact supporting member whereby to act upon the walls of the slots to start the pivotal movement and the riding of the spring over the corner edge of the block, said spring holding said movable contact supporting block upon riding over the corner edge and the push button means drawn inwardly upon riding over the corner edge and means operable upon the push button means and the transverse portion thereof to overcome the action of the leaf spring and to return the end thereof over the corner edge and the movable contact from engagement with the fixed contacts.

2. A push button bi-turn single pole switch comprising a switch housing, fixed contacts connected to the housing, a movable contact adapted to engage with the fixed contacts, a movable contact supporting block pivotally connected to the switch housing, said block having a corner edge, a leaf spring having an end rideable over the corner edge, said block having elongated slots, push button means having a transverse portion extending into the slots of the movable contact supporting member whereby to act upon the walls of the slots to start the pivotal movement and the riding of the spring over the corner edge of the block, said spring holding said movable contact supporting block upon riding over the corner edge and the push button drawn inwardly upon riding over the corner edge and means operable upon the push button and the transverse portion thereof to overcome the action of the leaf spring and to return the end thereof over the corner edge and the movable contact from engagement with the fixed contacts, said means for withdrawing the push button means comprising a turn knob engageable with the push button means to effect the rotation of the push button means and is transverse portion operable in the slot of the movable contact supporting block and a supporting body connected to said switch housing for slidably receiving the push-button means and for rotatably receiving the turn knob.

3. A switch construction comprising a switch housing, a fixed contact on the switch housing, movable contact means comprising a supporting block and a contact engageable with the fixed contact, means for pivotally connecting said supporting block to the housing, said supporting block having a corner edge, spring means operable over the corner edge of the block to hold the same in either the open position of the movable switch contact or in the closed position of the movable switch contact, said supporting block having an elongated slot, a bar operable in said slot, a plunger supporting body connected to the switch housing, a push button plunger operable through the plunger supporting body, said plunger having an extension rigidly connected to said transverse bar in the slot of the movable contact supporting block, a spring acting upon the plunger to urge the push button plunger outwardly from the switch housing, said push button plunger having an arm projection on the side thereof, a turn knob surrounding the push button and having an internal slot for receiving the arm projection of the push button plunger, means for connecting the turn knob to the plunger supporting member for rotation relative thereto, said turn knob being actionable upon the push button plunger to rotate its extension and the transverse bar within the slot of the movable

contact supporting block whereby to urge the corner edge of the block over the spring means to move the movable switch contact to an open position.

4. A switch construction comprising a switch housing, a fixed contact on the switch housing, movable contact means comprising a supporting block and a contact engageable with the fixed contact, means for pivotally connecting said supporting block to the housing, said supporting block having a corner edge, spring means operable over the corner edge of the block to hold the same in either the open position of the movable switch contact or in the closed position of the movable switch contact, said supporting block having an elongated slot, a bar operable in said slot, a plunger supporting body connected to the switch housing, a push button plunger operable through the plunger supporting body, said plunger having an extension rigidly connected 20 to said transverse bar in the slot of the movable contact supporting block, a spring acting upon the plunger to urge the push button plunger outwardly from the switch housing, said push button plunger having an arm projection on the side thereof, a turn knob surrounding the push button and having an internal slot for receiving the

arm projection of the push button plunger, means for connecting the turn knob to the plunger supporting member for rotation relative thereto, said turn knob being actionable upon the push button 5 plunger to rotate its extension and the transverse bar within the slot of the movable contact supporting block whereby to urge the corner edge of the block over the spring means to move the movable switch contact to an open position, and 10 said push button plunger having a longitudinal groove, a spring detent pin operable in said plunger supporting member and entering said groove to prevent the rotation of the plunger when the same is withdrawn and adapted to ride 15 out of the groove when the plunger is depressed to release the plunger for rotation by said turn knob.
